W. M. SCHOLL

ARCH SUPPORT

Filed April 2, 1925

UNITED STATES PATENT OFFICE.

WILLIAM M. SCHOLL, OF CHICAGO, ILLINOIS.

ARCH SUPPORT.

Application filed April 2, 1925. Serial No. 20,050.

To all whom it may concern:

Be it known that I, WILLIAM M. SCHOLL, a citizen of the United States, and a resident of the city of Chicago, in the county of Cook and State of Illinois, have invented certain new and useful Improvements in an Arch Support; and I do hereby declare that the following is a full, clear, and exact description of the same, reference being had to the accompanying drawings, and to the numerals of reference marked thereon, which form a part of this specification.

The invention relates to an improvement in arch supports for the longitudinal inner and transverse arch of the human foot.

One of the objects of the invention is to improve devices of this character.

Another object is to improve arch supports, of the character herein disclosed, wherein the arch-supporting plate is made relatively wider than that heretofore disclosed in my Patent No. 880,245 dated February 25th, 1908, to also extend under the outer longitudinal arch of the foot to afford a larger area of support for the foot and in which the arch-plate is made relatively shorter so as to not extend under the location of the oscalcis of the foot.

Another object is to make the rear end of the leather cover-plate of sufficient length to extend rearwardly to lie fully and completely under the oscalcis of the foot, to be formed into a rounded socket to receive the heel by the effect of the weight imposed thereon, the rear portion of the leather cover-plate being sufficiently wide to contact the vertical wall of the heel of the shoe so as to not form sharp edges thereunder.

Another object is to cover the forward end of the spring-plate and of the arch-plate by a relatively soft pad attached to the foremost plate to prevent the end of the spring-plate from wearing into the underlying part of the shoe, said cushion being skived at its front end to prevent an abrupt shoulder, to the discomfort of the wearer, and which pad is placed with its longest axis transverse to the plane containing the longitudinal arch and underlies the sesamoid and the metatarsal bones of the foot and affords them proper and sufficient support to maintain them in their normal natural position.

Other objects, advantages and benefits will become readily apparent to persons skilled in the art, from a proper consider-

ation of the following description, when taken in conjunction with the drawings, wherein:

Figure 1 is a bottom plan view of the arch support to be described herein.

Figure 2 is a longitudinal section through a shoe containing the foot and the improved arch support.

Figure 3 is substantially a longitudinal inverted section taken on line III—III of Figure 1.

Figure 4 is a transverse inverted section taken substantially on line IV—IV of Figure 1.

Figure 5 is an inverted section taken substantially on line V—V of Figure 1.

Figure 6 is a top plan view of the cover-plate formed of leather, or like material.

In all the views the same reference characters are employed to indicate similar parts.

The device consists, in general, of a resilient metallic arch-plate, longitudinally curved or arched to conform substantially to the longitudinal inner arch of the foot. A resilient metallic spring-plate underlies the arch-plate and is curved longitudinally on a radius longer than the radius upon which the arch-plate is curved, as clearly shown in the drawings. The spring-plate is secured to the arch-plate and to the cover-plate near the rear end of the two metallic plates, and at its front end the spring-plate extends forwardly of the arch-plate and receives the front end of the arch-plate in sliding contact therewith. A cover-plate of leather, or other suitable flexible material and shaped to fit properly in the interior of the shoe and to be worn under the foot, covers both plates and is skived to a thin edge at its front, and side, which latter is curved upwardly.

The rear end of the spring-plate does not extend rearwardly of the arch plate and is not located at any time under the heel of the wearer.

In the construction shown, 10 indicates the arch-plate which is curved transversely on one edge 11 and is curved to a less extent on the opposite edge 12. The arch-plate is curved longitudinally and transversely to snugly underlie the normal longitudinal inner and transverse arch of the foot, and extends laterally in a curved form to a less extent under the outer longitudinal arch of the foot. The front end of the arch-plate

is sufficiently wide to underlie the metatarsals of the foot or to extend substantially co-extensive therewith. I prefer that the arch-plate be made of sufficient width to underlie 5 all of the metatarsal bones and the cuneiform bone, thus to give support and to maintain the scaphoid and the astragalus, so that all of the overlying portion of the foot may thereby be maintained in its natural normal 10 position. The underlying spring-plate terminates at substantially the rear end of the arch plate, and at this point they are connected together by rivets 14. The spring-plate 13 is of greater length at its forward 15 end than the arch-plate, and to the front end of the spring-plate is attached a pad 15, skived into a thin front edge 16. The pad 15 has its longest axis located in a plane substantially at right angles to the longest plane 20 of the device and underlies the metatarsal and the sesamoid bones of the foot. The cover plate, 17 of leather, is also skived to a thin edge at its front end, as at 18, and together with the pad 15 which is normally in 25 contact therewith, the front ends of the two metal plates are enclosed. The pad 15 elevates the front end of the device to position to normally support the transverse or anterior metatarsal arch, and at the same time 30 it prevents the sharp end of the spring-plate from contacting and cutting into the exposed surface of the shoe. The arch-plate 10 is connected at its front end to the cover-plate 17 by a rivet extending through both 35 plates, but the front end of the two underlying plates, 10 and 13, are not so connected together. The rear end 19 of the leather cover-plate 17 extends to the rear end of the shoe, as at 20, so that the heel of the foot of 40 the wearer will produce a curved socket, as shown at 21 more clearly in Figure 5. The rear ends 22 and 23 of the metal plates do not extend under the oscalcis of the foot, so that the cushion formed by the part 19 of the 45 cover-plate is soft and yielding and the rear portion 19 of the cover-plate prevents the device, as a whole, from working rearwardly when the wearer is using the arch support. The pad 15 is secured to the spring-plate 13 50 by rivets 23.

The foregoing description, when taken in conjunction with my former patent to which reference has heretofore been made is a complete disclosure of the present invention.

Having described my invention what I 55 claim is new and desire to secure by Letters Patent is:—

1. An arch support comprising a resilient metal spring plate sufficiently wide to underlie the tarsal and metatarsal bones of the 60 foot, said plate curved longitudinally throughout its length and curved outwardly and transversely at its inner edge near its longitudinal mid-portion, said plate terminating rearwardly in front of the tuberosity 65 location of the oscalcis; a spring plate underlying said arch-plate, curved longitudinally on a longer radius than the radius of the longitudinal curve of the arch-plate, said plates connected together at their rear ends; 70 a pad connected to the front end of the spring-plate for underlying the metatarsal and sesamoid bones of the foot and a flexible covering for said plates terminating near the front edge of said pad and at the rear boundary of the shoe heel, said pad and the front edge of said cover-plate enclosing the front 75 ends of said arch-plate and spring-plate.

2. An arch support comprising a metal spring-plate for underlying the tarsal and 80 metatarsal bones of the foot, said plate curved longitudinally throughout its length and curved transversely and upwardly near its mid-portion to support the inner longitudinal arch of the foot, said plate terminating 85 rearwardly in front of the tuberosity location of the oscalcis; a spring-plate underlying said arch-plate curved longitudinally on a longer radius than the radius of the longitudinal curve of the arch plate, said spring- 90 plate connected to the arch-plate in front of the latter's rear end; a pad connected to the front end of the spring-plate having its longest axis in a transverse plane and a leather cover-plate connected to the arch 95 plate and having its rear end of length to rest in the heel seat of a shoe.

In testimony whereof I have hereunto subscribed my name.

WILLIAM M. SCHOLL.
